Leonard Day

UNITED STATES PATENT OFFICE.

FRANK CAPDEVILA, OF NEW YORK, N. Y.

HAIR CURLER.

Application filed February 28, 1927. Serial No. 171,495.

This invention relates to the art of hair curling, often referred to as permanent waving, and bears more directly upon the curler adapted for use in this art. In practising this art, it is necessary first to confine locks of hair in a tight helical curl, which curl is then subjected to heat and different re-agents tending to fix the curl in the hair. Heretofore, many curlers have been designed for this purpose, most of which have one or another defects. The object of the present invention is to supply a hair curler substantially free from defects, relatively cheap, and simple in construction and operation, and one which is practically universal in its function. For example, it is an objective that the tuft of hair to be curled may be wound with or without a twist of the tuft or strand of hair either in a right or a left-handed direction, and will conform cooperatively with any of the well-known heat applying devices. A further object of the invention is to provide for the firm gripping of the tuft of hair to be curled at the locality of the scalp, doing away with slipping or the necessity of tying the tuft of hair to the curler. A further object of the invention is to effect this gripping both for left and right-handed curling. A further object of the invention is to provide mechanism itself effecting a winding of the tuft of hair upon the curler, eliminating the necessity of grasping the tuft of hair with the fingers to effect this winding. Finger winding usually effects a twist of the strand which is more often undesirable, while the automatic winder embodied in my invention may at will wind the hair with or without twist, or by an added finger manipulation with a twist. A further objective in connection with the winder is to fabricate it in such a way as to cause it to function as a lock for the wound curl of hair upon the curler, thus doing away with the necessity of tying the ends of the curl.

A further object of my invention is to provide mechanism capable of giving to the wound tuft of hair an additional forcible wind tending to effect a tighter curl than that normally produced by the function of the winder alone.

In fact, the full object of my invention is to simplify in a hair curler of this type, the functioning parts, produce new combinations and correlations, all of which tend

to produce a more efficient hair curler than has heretofore been available for use.

The above will better be understood by reference to the illustrative embodiments of my invention, to which the following specification is directed for the purpose of illustrating the subject matter embodied in the following claims, and the same are shown in the accompanying drawings, which form a part hereof, all for purposes of illustration and not limitation.

In the drawings,

Fig. 1 is a front elevation of one of my curlers with a strand or tuft of hair wound ready for curling;

Fig. 2 is a side elevation with parts broken away, and the relation of parts indicated by dotted lines;

Fig. 3 is a fractional elevation of the central shaft;

Fig. 4 is a distal end view of the structure;

Fig. 5 is a section showing the gripper end from the opposite face relatively to that shown in Fig. 4;

Fig. 6 is a diagrammatic view with parts broken away, showing the co-axial arrangement of the parts of the shaft;

Fig. 7 is a fractional axial section, parts being shown in elevation;

Fig. 8 is a front elevation of the end spring construction; and

Fig. 9 is a proximal end view showing the clutch mechanism for inter-relating the outer and intermediate tubular parts.

Referring more in detail to the drawings, the structure as shown particularly in Fig. 1, comprises primarily three parts, an elongated multiple shaft A, upon which the strand of hair 1 is to be wound; a gripper mechanism B at the distal end, and a mechanical winder means C riding on the shaft A. In its preferred form, the shaft A comprises a central shaft or stem 3 with the combination guard and gripper part 4 fixed thereto as by riveting. This gripper part 4 comprises two horns 5 and 6, directed towards each other, and outlying a central hub 7 so that an entrance mouth 8 for the lock of hair 1 is provided between the tips of the horns and a right and a left-handed gripping channel 9 and 10 merge from the mouth 8. It is preferred that the exterior of this gripper part 4 be provided with knurling 11 to provide a secure finger grip. The co-

operating gripper part or foot 12 also has teeth or knurling 13 provided on the outer cooperating face of the structure to assist in holding the foot 12 in gripping engagement with the strand of hair, which may be crowded against one of the gripping edges 15 or 16.

The foot 12 is formed preferably as an axial extension from the intermediate tubular shaft 17 overlying the stem 3 co-axially therewith, and provided at its proximal end with out-turned clutch fingers 18, located in notches 19 of the friction sleeve 20.

Mounted about the intermediate tube 17 is an outer tube 21 which from the demarking line 22 to its proximal end is preferably knurled or roughened to provide a firm finger grip or a grip for a pair of pliers. The friction sleeve 20 bears against the end of this outer tubular part 22 with frictional engagement. It is preferred that a compression spring 23 be employed to increase the frictional cooperation between the three parts of the shaft. This is accomplished preferably by fixing a bushing 24 to the proximal end of the central shaft 3 and providing a loose friction bushing 25 between the spring 23 and the friction sleeve 20. By this spring arrangement, one or both of the outer tubular shafts are thrust towards the distal end of the structure towards the gripper part 4.

Riding on the outer tube 21 is the automatic winder C which is formed preferably of resilient sheet metal having gripper means frictionally holding the winder to the outer sleeve 21, although by the application of a manipulating force as to the wings 31 may be caused to rotate either with or on the outer sleeve 21 and to be moved axially thereon. This winder is constructed to function both as a right or a left-handed winder having similar notches 33 and 34, formed in front of winding horns 35 and 36, which provide an entrance slot therebetween for the strand of hair 1. This winder C also functions as a lock or binder for the wound strand of hair, eliminating all necessity for tying off the end of the wound strand.

In its operation, to effect a right-handed twist, as shown in Fig. 1, a strand of hair 1 is slipped sidewise through the mouth 8 into the passage 9. The foot 12 is rotated by means of a finger twist upon the part 20, the fingers of the other hand holding the part 4 until the foot 12 forcibly clamps the strand of hair against the gripping wall 15 up near the scalp. The projecting lock of hair is then inserted between the horns 35 and 36 of the winder, which is finger-rotated by means of the lip 31 in a right-handed direction. The lock of hair then automatically forms its own twist or helix about the outer tube 21, the winder C moving outwardly in a proximal direction, as the strand of hair

is wrapped about the sleeve 21. The rotation of the winder by friction imparts a tightening effect upon the gripper foot 12, and also the desired degree of winding upon the outer tube 21 under the entire strand of hair as it is wound up. In some cases, the tightness of the twist is not as great as may be desired from the effect of the winder C alone. When an extra degree of tightness is required, with the gripper part 4 held in the fingers of one hand, a pair of pliers may be applied to the knurled end 40 of the outer tube 21 to give a finishing twist to the strand of hair 1, with the twisting movement applied throughout the entire strand on its own face, instead of wholly at one end as by the winder. During this operation, the winder C locks the strand of hair in its closed convolutions about the outer tube 21 while the friction effected by the compression spring 23 is sufficient to prevent an unwinding of the strand.

In its fabrication, I prefer to employ all metal for my structure so that the whole may be heat-sterilized. Suitable materials are brass, nickel plated steel, and aluminum. Although I have illustrated a preferred embodiment of my entire structure, I desire it to be understood with definiteness that many separate elements and combinations of elements short of the whole are viewed by me as novel and constituting a part of my whole invention.

What I claim and desire to secure by United States Letters Patent is:

1. A hair curler comprising three concentric shafts, the outer two of which are tubular; a two-part gripper fixed to the distal ends of two of said shafts and operable independently of the other of said shafts; the outermost shaft being positioned between the other shafts and the hair; and a winder clip riding upon the said outermost tubular shaft and being frictionally gripped thereto.

2. A hair curler comprising a tubular part upon which the hair is to be wound and an inner shaft, a combination right-hand and left-hand hair gripper for the distal end of said structure; a combination right and left-hand winder riding upon said tubular part, having frictional engagement therewith, and movable thereto both axially and circumferentially; and means tending to hold said gripper in gripping condition.

3. A hair curler comprising a shaft upon which the hair to be curled may be wound; a manually operable gripper forming a part of said mechanism located at the distal end of the structure and adapted firmly to grip a tuft of hair to be curled at the locality of the scalp; a winder circumferentially and axially movable upon said shaft frictionally gripped thereto and capable upon manipulation of winding a tuft of hair upon said shaft and having means for holding said

tuft of hair upon said shaft in wound condition.

4. The structure as defined in claim 3 and further characterized by the fact that said shaft comprises a rotatable outer part adapted for direct contact with the hair, which may be rotated independently of said gripper to effect a tightening of the hair wound thereon.

5. A hair curler comprising a shaft in the form of a plurality of relatively movable

co-axial parts; a gripper for grasping a tuft of hair and located at the distal end of such structure; a hair winder for automatically winding a tuft of hair upon said shaft without twisting it and having means for holding the tuft of hair in wound position; and provisions for frictionally holding said winder against counter-rotation relatively to said gripper. 15
